a corporation of California

Application January 30, 1958, Serial No. 49,444

Term of patent 14 years

(Cl. D13—1)

Fig. 1 is a side perspective view of a room divider unit showing my new design.

Fig. 2 is a vertical section taken on line 2—2 of Fig. 1.

Fig. 3 is a section taken on line 3—3 of Fig. 1.

Fig. 4 is an elevational view taken from the left of Fig. 1.

The side opposite that shown in Fig. 1 is substantially the same as that illustrated.

The essential features of my design reside in the features shown in full lines.

I claim:

The ornamental design for a room divider unit, as shown and described.
